UNITED STATES PATENT OFFICE.

FRANK DOUGLAS, OF CHICAGO, ILLINOIS.

DESIGN FOR A CHAIN AND SPROCKET-WHEEL GUARD FOR BICYCLES.

SPECIFICATION forming part of Design No. 31,866, dated November 21, 1899.

Application filed August 14, 1899. Serial No. 727,134. Term of patent 7 years.

To all whom it may concern:

Be it known that I, FRANK DOUGLAS, a citizen of the United States, residing at Chicago, in the county of Cook and State of Illinois, have invented and produced a new and original Design for a Chain and Sprocket-Wheel Guard for Bicycles, of which the following is a specification, reference being had to the accompanying drawings, showing the guard detached from a bicycle-frame.

Figure 1 is a perspective view of my guard without the clamp-fastenings for attaching it to the frame of a bicycle and shows the shape and design of the straight reach C, which terminates at its forward end in a curved covering for the upper front teeth of a front sprocket-wheel. The downcurved part B is the continuation of the curved sprocket-cover back and down below the reach C and is made in angle form below the reach to cover the face and the outer side of the sprocket-wheel teeth. Fig. 2 is a cross-section of the reach C and shows its angle shape. Fig. 3 is a cross-section of the curved part A, cut through at 8 8, and shows the curved and angular-shaped projection B over the back face of the sprocket-wheel below the reach C.

The leading features of my design consist in a light half-circle sprocket-cover with a tangential straight reach back over the chain, 30 the whole in an angle form to cover only the top and the outside of the upper line of chain and about the upper one-half of a front sprocket-wheel. This gracefully -designed guard covering only the upper chain and 35 upper part of the sprocket-wheel is all the protection required to protect the clothing of a rider and takes the place of the cumbersome and unsightly guards that extend below the lower chain and are laced or connected by 40 metal strips from the upper to the lower reach.

My guard is lightened by round and oblong openings in the outer side of the curved part and also by a triangular opening at the junction of the curved part A and the straight 45 part C.

What is claimed is—

The design for a driving-chain and sprocket-wheel guard for bicycles, as herein shown and described.

FRANK DOUGLAS.
